Patented July 31, 1917.

UNITED STATES PATENT OFFICE.

ROBERT R. BARTLETT AND WILLIAM H. McCCLAIN, OF HOOD RIVER, OREGON, ASSIGNORS
TO EDWARD T. BURROWES, OF PORTLAND, MAINE.

TABLE.

1,235,416.

Specification of Letters Patent. Patented July 31, 1917.

Application filed July 21, 1913. Serial No. 780,190.

To all whom it may concern:

Be it known that we, ROBERT R. BARTLETT and WILLIAM H. McCCLAIN, both citizens of the United States, and both residing in the city of Hood River, county of Hood River, and State of Oregon, have invented certain new and useful Improvements in Tables, of which the following is a specification.

The principal object of our invention is to provide a table having a reversible table top, the opposite sides of which are adapted for different purposes, and the legs of which are foldable, thereby providing a portable table having a reversible top and also capable of being folded into small compass.

It is often desired to have a number of small portable tables which can be used for card or game tables, and which can also be quickly adapted for light refreshments or other purposes requiring a different top or covering. To this end it is desirable to have a table with a reversible top, the opposite sides of which are adapted for different purposes, and which can be quickly and conveniently changed.

We have shown one practical embodiment of our invention in the accompanying sheet of drawings for purposes of illustration, which we will now describe, in order to enable others to understand it. In the drawings,

Figure 1 is a side elevation of a table embodying our invention, with parts broken out of the legs to reduce the size of the figure;

Fig. 2 is a bottom plan view of the table frame with the legs in folded positions, the top not being shown;

Fig. 3 is a fragmentary sectional view taken on line 3—3 of Fig. 1;

Fig. 4 is a fragmentary sectional view taken on line 4—4 of Fig. 5;

Fig. 5 is an enlarged fragmentary view of one corner of the table, with top omitted and showing a means of foldably attaching the legs thereto; and

Fig. 6 is a detail view showing how the end of a brace wire is held in operative position with the leg down.

Referring now to the drawings, the table here shown for purposes of illustration, is of square construction, and comprises four frame pieces, 1, 1, 1, 1, secured together at the corners in any desired manner, being cut away or grooved around their upper inside faces, as indicated at 2, Fig. 3, whereby

to provide a receiving support for a detachable and reversible table top, designated as a whole as 4, and comprising a square frame made of strips of the cross sectional form shown as 5, Fig. 3, to the opposite sides of which frame are secured table tops 6 and 7, which may be made of, or covered with, different materials, such as felt, or soft fabric on one side, or leather, glass or other desirable material on the opposite side, depending upon the use to which it is to be put.

The table top frame 5 is detachably secured in the table frame 1 by means of spring-actuated plunger stops, set in the frame pieces, as indicated in dotted lines at 8, Fig. 3, two or more of these holding studs being placed in each of the four sides of said table frame, and adapted to fit into suitable seats formed in the edges of the table top frame 5, as clearly illustrated in Fig. 3.

The four legs 9 of the table, when folded, lie parallel with and adjacent to the sides of the frame. For connecting the legs with the table, we have provided a novel form of bracket *d*. Each bracket is formed so as to space the leg attached to it a suitable distance from the side of the frame with which the leg lies parallel when folded, so as to permit room for the operation of the brace 12, and the bracket is also provided with a part which engages the end of another leg when folded. The several brackets are alike in construction. As shown, each comprises a strip of metal bent or otherwise formed at its center into a U-form or yoke, as indicated at 10, and the leg 9 is pivoted within the yoke by a pivot pin 9^a. The central portion 10^a of the yoke 10 is secured by suitable fastening means to one side bar of the table frame, and one arm of the yoke is off-set, as indicated at 10^b, and secured to the adjacent side bar of the frame, this offset portion of the arm spacing the yoke and the leg a fixed distance from the latter bar.

The opposite arm of the yoke has an overturned end 10^c, which engages the side of another table leg, when folded, and holds the latter in folded position. Thus, each bracket *d* serves to pivotally support one of the legs in its proper position and has a means for engaging another leg, arranged at right angles thereto when the latter is folded. Each table leg is provided with a spring wire brace member, 12, secured thereto at one end, as at 13, and extended through two staples, as 14—14, in the frame members 1. The end

of said spring brace member is formed into a holding hook, as 12', substantially as shown in Fig. 6, whereby when the leg is extended or open, the hooked end 12' of said brace member snaps into holding engagement with the end staple 14, as clearly illustrated in Fig. 6, whereby to prevent the leg from closing until the end of the spring wire brace member 12 has been flexed and allowed to move through the staples 14. The legs are foldable wholly within the frame members 1 and the table when folded is no thicker than the breadth of said table frame pieces 1, 1, unless the top be mounted to project slightly above the edges of the frame pieces. To reverse the table top it is only necessary to push it upwardly from the underside, turn it over and press it back into place again, the spring actuated plungers 8 all being so placed, relative to the seats in the edge of the table top that this can be done.

While we have shown and described one practical form of the invention, we are aware that changes can be made therein without departing from the spirit of the invention, and we do not, therefore, limit the invention to the particular form shown for illustrative purposes, except as we may be limited by the hereto appended claims.

We claim:

1. In a folding table, an angular frame, leg-supporting brackets secured to the frame at its corners, each bracket comprising a yoke having its central portion fitting against one side bar of the frame and having one arm offset and fitting against the adjacent side bar, to space the yoke from said latter bar, and legs pivoted between the arms of the yokes.

2. In a folding table, a rectangular frame, leg supporting brackets arranged within the frame at its corners, each bracket comprising a yoke having its central portion fitting against one side bar of the frame, and having the end portion of one arm offset outwardly against the adjacent bar and the end of its other arm turned inwardly substantially parallel with the first mentioned bar, and legs pivoted within the several yokes, each leg adapted, when folded, to engage the inwardly turned arm of a yoke at the opposite side of the frame.

ROBERT R. BARTLETT.
WILLIAM H. MCCLAIN.
